UNITED STATES PATENT OFFICE

PHILIP A. WOOSTER, OF SAN FRANCISCO, CALIFORNIA

DESIGN FOR A SOAP-DISPENSER

Application filed September 30, 1931. Serial No. 41,275. Term of patent 14 years.

To all whom it may concern:

Be it known that I, PHILIP A. WOOSTER, a citizen of the United States of America, residing in the city and county of San Francisco, State of California, have invented a new, original, and ornamental Design for Soap-Dispensers, of which the following is a specification, reference being had to the accompanying drawings, forming part thereof.

Fig. 1 is a plan view of a soap-dispenser, showing my new design; and

Fig. 2 is a side elevation of the same.

I claim:

The ornamental design for a soap-dispenser, as shown.

PHILIP A. WOOSTER.
